Inventor:
Mathias Dochnal.
By *Fred J. Marson*
Attorney.

UNITED STATES PATENT OFFICE.

MATHIAS DOCHNAL, OF ST. LOUIS, MISSOURI.

TILE-BLOCK.

1,396,265.

Specification of Letters Patent.

Patented Nov. 8, 1921.

Application filed October 28, 1918. Serial No. 259,963.

To all whom it may concern:

Be it known that I, MATHIAS DOCHNAL, a citizen of the United States, residing in the city of St. Louis and State of Missouri, have 5 invented certain new and useful Improvements in Tile-Blocks, of which the following is a specification.

My present invention consists in an improved building tile block of special novel 10 construction, and has for its object to provide a tile block which can be cheaply manufactured by reason of its shape and be practical for any style of wall structure such, for instance, as chimneys, tanks, silos 15 and the like.

With the above and other objects in view, the invention consists in the novel construction hereinafter described and finally pointed out in the claim hereto appended.

20 Referring to the accompanying drawings, forming a part of this specification wherein like characters of reference denote similar parts throughout the several views:

Figure 1 is a top plan view of a tile block 25 formed in accordance with my invention.

Fig. 2, is an end view thereof.

Fig. 3, is a sectional view of the tile taken on line X—X of Fig. 1.

In carrying out the aim of my present invention, I form a tile block consisting of the 30 inner wall section 1 and the outer wall section 2. The inner and outer wall sections are united by means of a central cross-wall 3 having the upper curved, or concaved face 35 4. The uniting cross-wall 3 is so shaped as to form a semicircular opening 5 at each end of the tile block.

The inner face of the inner and outer wall sections 1 and 2 are each provided with a 40 facial rib 6 formed at each end of the wall sections arranged in opposed relation and extending into the semicircular openings 5 to provide a contracted end opening or space 7 at each end of the tile. One face of each 45 of the ribs 6 is beveled, as at 8 and the upper face of each rib 3 is curved or concaved, as at 8, to conform to the curvature of the upper face of the uniting cross-wall 3. This curved upper face permits the use of horizontal reinforcing rods being used in a wall 50 structure.

This form of tile block, it will be observed, is substantially I-shaped in forma-

tion and can be easily and cheaply made and handled.

When these tile-blocks are laid in end to end relation in a wall structure, it will be understood that a substantially circular opening will be formed at the break joint of adjacent tile due to two semicircular end 55 openings being arranged side by side. The two adjacent tile blocks in a course are adapted to be interlocked end for end through the medium of a cement filling placed in the opening to form a solid core 60 or column on each side of the central cross-wall as is manifest.

The many advantages of the herein described invention will readily suggest themselves to those skilled in the art to which it 70 appertains.

I do not desire to be understood as limiting myself to the details of construction and arrangement as herein described and illustrated, as it is manifest that variations 75 and modifications may be made in the features of construction and arrangement in the adaptation of the device to various conditions of use without departing from the spirit and scope of my invention and the 80 terms of the following claim, hence I wish it to be understood that I reserve the right to make any such changes or modifications as may fairly fall within the scope of the appended claim when fairly construed. 85

What I claim is:

A tile block comprising an inner wall section and an outer wall section, a central cross-wall uniting said inner and outer wall sections, said cross-wall having concaved end 90 faces to gradually strengthen its union with the inner and outer wall sections and provide a semi-circular opening at each end of the tile block, a facial rib formed at each extremity of the inner and outer wall section, said ribs each having a beveled inner face 95 uniting with the ends of the cross-wall, said ribs extending inwardly in opposed pairs into the semi-circular end openings of the tile block to provide broad end faces for the 100 tile block, said cross-wall and said facial ribs each having their upper face concaved.

In testimony whereof, I have hereunto signed my name to the specification.

MATHIAS DOCHNAL.
